Attorney

UNITED STATES PATENT OFFICE.

WILLIAM O. BACKLUND, OF STROMSBURG, NEBRASKA.

CHECKREIN ATTACHMENT.

1,245,175.

Specification of Letters Patent.

Patented Nov. 6, 1917.

Application filed April 20, 1917. Serial No. 163,403.

To all whom it may concern:

Be it known that I, WILLIAM O. BACKLUND, a citizen of the United States, and resident of Stromsburg, in the county of 5 Polk and State of Nebraska, have invented certain new and useful Improvements in Checkrein Attachments, of which the following is a specification.

This invention relates to new and useful 10 improvements in buckles, and the primary object of the invention is to provide a new and improved check rein attachment, used for separating the reins, and preventing the same from turning over, or slipping, and 15 also from catching in the fly net.

Another object of the invention is to provide a device of this character, which is easily and simply constructed, inexpensive to manufacture, and one which will be very 20 efficient in operation.

With these and numerous other objects in view my invention consists of the novel features of construction, combination and arrangement of parts which will be herein- 25 referred to and more particularly pointed out in the specification and claims.

In the accompanying drawing:

Figure 1 is a plan view of my check rein attachment, showing the rein applied thereto; 30 Fig. 2 is a longitudinal section through the same.

In describing my invention I shall refer to the drawing in which similar reference characters designate corresponding parts 35 throughout the several views. This check rein attachment, is applicable to the type of check rein, wherein certain portions thereof converge, one of the converging portions extending rearwardly, and being connected 40 to the hook by which the rein is held, and the other portion being secured by this attachment.

The numeral 1 designates a buckle, formed of a substantially rectangular shaped 45 metal frame, and having a tongue 2 mounted on the rear side 3 thereof. Projecting from the rear side of the ends thereof, are diverging rods 4, which have their free ends connected by a vertically positioned strap 50 engaging loop 5. The strap is additionally held in position by a supplemental holding member, that connects the rods 4 adjacent their inner ends, and which is substantially half-looped shaped, the same being designated by the numeral 6.

The upper edge 7 of the loop 5 has piv-

otally mounted thereon a dividing pin 8, which is disposed centrally of said loop, and which extends downwardly across the same, having its lower edge engaging the bottom 60 edge 9 of said loop. This pin is positioned as has been stated centrally, and forms a dividing mark between the converging portions of the strap employed in this type of check rein. 65

In operation one of the converging portions of the check rein, which is designated by the numeral 10, has its end extending through the loop 5 between one side of the same and the dividing pin, and its extremity 70 is held in position by engagement with the tongue 2 of the buckle 1. The other converging portion of the check rein which is designated by the numeral 11 passes through the other portion of the loop 5, and is positioned over the portion 10 of said rein, this portion likewise being engaged by the tongue of the buckle 1, and said portion extends from the front end thereof as shown at 12, this portion of the checkrein being 80 connected with the hook, not shown, to hold the device in position.

This type of check rein attachment will securely hold the check rein in position, and prevent the buckle from slipping through 85 the ring on the harness and catching, and also from being entangled with the fly net. This attachment furthermore keeps the check rein in upright position, and prevents the same from turning over during use. 90 The attachment is very economically manufactured, owing to its extreme simplicity and it may be easily applied to the conventional type of check rein of this character now in use. 95

A check rein attachment of this character permits the reins to be shifted as desired, should it be necessary to change from a right line to a left line. The dividing pin owing to the fact that it is pivotally mounted may be swung upwardly, so as to allow the reins to shift. 100

From the foregoing description of the construction and operation of my new and improved type of check rein attachment, 105 the manner of applying the same to use and the operation thereof will be readily understood, and it will be seen that I have provided a simple and efficient means for carrying out the objects of this invention. Although 110 I have in this embodiment defined my check rein attachment specifically I do not wish

it to be understood as confining the invention to this particular type, nor the exact construction, arrangement and adaptation of parts shown and described, as I reserve the right to make any changes and alterations as fairly fall within the spirit and scope of the invention.

Having fully described my invention, what I claim as new, and desire to secure by Letters Patent, is:

1. A device of the class described including a buckle, a pair of diverging rods projecting from one end thereof, a transversely extending vertical loop connecting the free ends of said rods, and a centrally disposed

dividing pin extending between the upper and lower edges of said loop.

2. A device of the class described including a buckle, a pair of diverging rods projecting from one end thereof, a transversely extending vertical loop connecting the free ends of said rods, a supplemental holder connecting said rods, and a centrally disposed vertical dividing pin pivotally connected with one edge of said loop and normally disposed between the upper and lower edges of the same.

In testimony whereof, I affix my signature hereto.

WILLIAM O. BACKLUND.

Copies of this patent may be obtained for five cents each, by addressing the "Commissioner of Patents, Washington, D. C."
